UNITED STATES PATENT OFFICE.

WILLIAM A. KELSEY, OF MERIDEN, CONNECTICUT.

IMPROVEMENT IN PRINTING-PRESSES.

Specification forming part of Letters Patent No. 138,660, dated May 6, 1873; application filed April 3, 1873.

To all whom it may concern:

Be it known that I, WILLIAM A. KELSEY, of Meriden, in the county of New Haven and State of Connecticut, have invented a new Improvement in Printing-PresSES; and do hereby declare the following, when taken in connection with the accompanying drawing and the letters of reference marked thereon, to be a full, clear, and exact description of the same, and which said drawing constitutes part of this specification, and represents, in—

Figure 1, a side view; Fig. 2, a top view; Fig. 3, a section on line *x x*, looking down.

This invention relates to an improvement in that class of printing-presSES designed for small work, and generally termed toy-presSES; and it consists, first, in a bed in nearly a vertical position, attached to a frame, and a swinging platen pivoted to the frame below, combined with a lever pivoted to the platen, and with trunnions on the said lever, which traverse up and down an inclined surface on the frame to open and close the press; and, secondly, in constructing the chase with a bottom and with projecting ends, so as to be set upon the bed and secured thereto by means of the said projecting ends.

A is the frame, preferably in two parts, arranged near together at the center of the press, as seen in Fig. 2. Arms B extend up and are attached to or formed upon the bed C. D is the platen, formed with an arm or arms, E, which extend down and are hinged to the frame, as at *e*, the pivot being arranged relatively to the platen, so that when the platen is thrown up to the bed for the impression it will come parallel with the bed on a line with the surface of the type. In front of the platen arms F extend up, with their inner surface inclined. To the platen one arm, G, of the lever is pivoted, as at *g*; this lever extending so as to form the handle H. On the lever trunnions or rolls I are arranged, so that when the lever is depressed, as denoted in broken lines, these trunnions will run down the incline, forcing the platen from the arm and toward

the bed, the lever gradually assuming a position at right angles to the said inclined surface, and arriving nearly or quite at right angles when the platen has been sufficiently far thrown up to produce the impression; raising the lever, the plate falls back, as denoted in Fig. 1.

In the construction of the chase I form the frame L of the requisite size, and provided with a bottom, P, forming, practically, a box the depth of the chase, so that the type may be set directly in the box, without the use of a composing-stick, and, when set, may be locked up in the usual manner, thus enabling me to dispense with the composing-stick, which complicates the use of this class of presses. To secure the chase to the bed I construct the chase with projecting ends R and apply to the bed springs S, or other clamping device, which will set up over the projecting ends R and bear thereon with sufficient force to hold the chase in place; and to adjust the chase, so that the surface of the type will conform to the surface of the platen, I arrange adjusting-screws through the bed, by means of which the bed may be elevated or depressed, as required.

I claim as my invention—

1. The herein-described press, consisting of the frame A supporting the bed C, and the platen D pivoted to the said frame below the bed, the lever G H pivoted to the said platen, and with trunnions working upon the inclined arms to give the requisite movement to the platen, substantially as set forth.

2. In a printing-press, substantially such as described, the chase L, constructed with a bottom, P, and with projections R, combined with a clamping device, S, substantially as specified, and with or without the adjusting-screw *a* through the bed.

WM. A. KELSEY.
